US00D871133S

(12) **United States Design Patent** (10) **Patent No.:** **US D871,133 S**
(45) **Date of Patent:** **** Dec. 31, 2019**

(54) **LID**

(71) Applicant: **YETI Coolers, LLC**, Austin, TX (US)

(72) Inventors: **Dustin Bullock**, Austin, TX (US);
Edward Abante, Austin, TX (US);
Evan Goldberg, Austin, TX (US);
Steve Charles Nichols, Austin, TX (US)

(73) Assignee: **YETI Coolers, LLC**, Austin, TX (US)

(***) Term: **15 Years**

(21) Appl. No.: **29/667,024**

(22) Filed: **Oct. 17, 2018**

(51) LOC (12) Cl. **07-99**

(52) U.S. Cl.

USPC **D7/392.1; D9/435**

(74) *Attorney, Agent, or Firm* — Banner & Witcoff, Ltd.

(57) **CLAIM**

The ornamental design for a lid, as shown and described.

DESCRIPTION

FIG. 1 is a top, front, right perspective view of a lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, right perspective view of a lid showing our new design in its exemplary environment;

FIG. 9 is a top, front, right perspective exploded view of a lid showing our new design;

FIG. 10 is a front view thereof;

FIG. 11 is a rear view thereof;

FIG. 12 a right side view thereof;

FIG. 13 is a left side view thereof;

FIG. 14 is a top view of our new design shown disassembled; and,

FIG. 15 is a top, front, right perspective exploded view of a lid showing our new design in its exemplary assembly.

The broken lines shown in FIGS. 8 and 15 depict environmental subject matter that forms no part of the claimed design.

1 Claim, 14 Drawing Sheets
